UNITED STATES PATENT OFFICE.

CARLOS B. MICHENER, OF PROSSER, WASHINGTON.

AUTOMATIC SWITCH-THROWING MECHANISM.

1,286,707.

Specification of Letters Patent. Patented Dec. 3, 1918.

Application filed September 6, 1916, Serial No. 118,680.

To all whom it may concern:

Be it known that I, CARLOS B. MICHENER, a citizen of the United States, residing at Prosser, in the county of Benton, State of Washington, have invented a new and useful Automatic Switch-Throwing Mechanism; and I do hereby declare the following to be a full, clear, and exact description of the invention, such as will enable others skilled in the art to which it appertains to make and use the same.

This invention relates to the art of traffic or railroad equipments, and more particularly to an improved automatic electrically operated switch mechanism, of such improved construction, that when a train is moving in one direction or the other, an electric circuit may be closed, to automatically throw the switch points.

Another object of the invention is to utilize the current generated from the usual dynamo or storage battery (which furnishes current for the usual electric lighting system of the train) for actuating an electric motor adjacent the rails and connected to the switch points, whereby the switch points may be thrown.

A further object of the invention is to provide means carried by the engine or by the end car of the train and adapted to be depressed into engagement with contact or terminal rails to close a circuit to actuate said motor, whereby the switch points may be actuated.

A further object of the invention is to provide automatic means so timed that when the motor shaft has made one half revolution, which is sufficient to throw the switch points, the circuit is automatically opened or broken, thereby instantly causing the motor to stop.

A further object of the invention is to provide means actuated by the motor to automatically lock the switch points when thrown or moved to their different positions.

In practical fields, the details of construction may necessitate alterations falling within the scope of what is claimed.

The invention comprises further features and combination of parts, as hereinafter set forth, shown in the drawings, and claimed.

In the drawings:

Figure 1 is a perspective view of a section of a railroad, showing the siding and the

switch points, and illustrating the means to be actuated for throwing the switch points.

Fig. 2 is a view partly in elevation and partly in section of the means carried by the engine or the end car of a train, and adapted to be actuated by the engineer or the conductor, to operate the means adjacent the rails to actuate the switch points.

Fig. 3 is a view partly in section and partly in elevation on line 3—3 of Fig. 2.

Fig. 4 is a sectional view on line 4—4 of Fig. 1, showing the connections between the switch point actuating means and the switch points.

Fig. 5 is a detail view of the means for locking the switch points after having been moved.

Fig. 6 is a detail view in elevation of an eccentric carried by the motor shaft to actuate the pitman which is connected to a connecting bar of the switch points.

Fig. 7 is a sectional view on line 7—7 of Fig. 6.

Referring more especially to the drawings, 1 and 2 designate the main rails, and 3 and 4 denote the siding rails, and 3^a and 4^a denote the switch points to be operated. Arranged between the main rails 1 and 2 are the two sets of secondary contacting rails 5 and 6, and 9 and 10, and between the siding rails are the two sets of secondary contacting rail sections 7 and 8, and 11 and 12. Arranged adjacent the main rail 1 is a conventional form of motor 40, the motor shaft 41 of which is provided with an eccentric 42 splined upon the shaft. This eccentric comprises the two circular plates 43, which are secured together by the screws 44. These circular plates have annular recesses, which, in cross section, are angular or L-shaped, and when said plates are secured together as shown in Fig. 7, these annular recesses form an annular groove 46, to receive the eccentric strap 47, which is carried by one end of the eccentric rod 48. The switch points 3^a and 4^a, as shown in Fig. 4, are connected by the bar 49, which is secured to said switch points by the bolts 50. The eccentric rod 48 is in turn connected to the bar 49 by the pivot pin 51, and in the bifurcation 52 of said bar 49. Secured on one of the ties is an angular bracket 53, which carries a solenoid 54, the core 55 of which is connected to a pivoted lever 56 (which is connected to a bracket 57 by means of a pivot pin 58) by

means of a link 59. The eccentric rod 48 is provided with a pair of notches 60 and 61, either of which can be engaged by the lever 56. The solenoid is connected to the motor 5 by the lead or wire 62 and carried by the motor shaft 41 are automatic cutoffs or circuit closers 80 and 82. The closer or cutoff 80 comprises the supporting member 80^a, which is stationary, and in a bearing of 10 which the shaft 41 rotates. On one face of the supporting member 80^a is a substantially semi-circular stationary contact terminal 17^a and a stationary contact terminal lug 80^a. Movable with but insulated from the 15 shaft 41 is a substantially semi-circular movable contact terminal 17 provided with a right angle extending arm 17^b. When the shaft 41 makes a half revolution, the member 17 substantially at the end of the half 20 revolution will contact with the terminal lug 80^a, and the arm 17^b will engage the stationary contact terminal 17^a. The cutoff or 25 circuit closer 82 comprises a stationary part 82^c in a bearing of which the shaft 41 is rotatably mounted. On one face of the stationary member 82^c is a substantially semi-circular stationary contact terminal 18. A 30 semi-circular movable contact terminal 18^a having an arm 18^b is carried by and insulated from the shaft 41. A contact lug 82^a projects from one face of the stationary support 82^c. It is to be observed that the contact terminal 18^a is engaging the lug 82^a, and the arm 18^b is engaging the terminal 18. 35 As the shaft 41 is making its half revolution, at the time of closing the circuit on the contacting rails 5 and 6, said contacting terminal 18^a will sweep in engagement with the lug 82^a and the stationary terminal 18, until 40 the terminal 18^a assumes a dotted line position out of engagement with the terminal 18, at which time the terminal 17 of the cutoff or closer will engage the lug 80^a, and the arm 17^b will engage the terminal 17^a. It is 45 to be noted that when the motor is actuated, the shaft 41 makes a half revolution, thereby causing the eccentric to make a half turn, thereby moving the eccentric bar, to pull upon the bar 49 which is connected to the 50 switch points, thereby throwing the switch points so that the train will pass on to the siding rails 3 and 4. When the motor is actuated, the solenoid is energized, causing the core 55 to be raised, lifting the lever 56 55 out of engagement with the notch 61, allowing the eccentric bar to operate. When the motor stops at the end of the half revolution of the motor shaft, the solenoid is deenergized, which will allow the core 55 to drop, 60 and the lever 56 to engage the notch 60.

As will be presently described, the motor is so wired in circuit with said terminal rail sections 5 and 6, 7 and 8, 9 and 10, and 11 and 12, that by closing a circuit on such terminal 65 rail sections by a suitable mechanism

(which is to be carried by the engine) just before a train enters the siding rails, the switch points may be opened. When the shaft 41 is again rotated a half revolution, the wiring is such, that when closing a circuit on the contacting rail sections 11 and 12, the eccentric of the shaft 41 will operate and close the switch points.

The mechanism to be carried by the engine or locomotive may comprise a storage 75 battery, dynamo, or the like, 66, from which current can be attained, in order to be conveyed or transmitted over the contacting rail sections 5 and 6, 7 and 8, 9 and 10, and 11 and 12, in order to operate the motor, by 80 means of a depressible device 67. Each train should be equipped with a storage battery, dynamo, or the like, in the cabin of the engine or elsewhere, and two depressible devices 67, one in the cabin of the engine, 85 the other in the end car or caboose of the train. Each depressible device 67 comprises a pair of vertical rods 68 mounted in the guides 59 of the wooden floor of the cabin or car, which have their upper ends connected by the transverse bar 70 of some suitable insulating material. Between the bar 70 and the floor of the cabin or car and surrounding the said rods 68 are the coiled springs 71, which act to hold the contacting 90 wheels 72 journaled upon the bolts 73 of the forks 74 of the lower ends of said rods 68, upwardly out of contact with the rail sections 5 and 6, that is, when the train is passing without throwing the switch points. 95 The storage battery or dynamo is provided with binding posts 75 and 76. The binding posts 75 are connected to the binding posts 70^a of the bar 70 of the depressible device in the cabin of the engine by the wires or leads 100 77. The binding posts 70^a extend through the bar 70 and connect in any suitable manner to the rods 68. The binding posts 76 are designed to be connected by the leads 78 to similar rods 68 of a depressible device, 105 not shown, to be carried in the end car or caboose of the train. However, these depressible devices may be varied in details of constructions.

A lead or wire 13 is connected to the contacting rail section 5, and is in turn connected at the junction 15^c with the wire 15^e. This wire 15^e is connected to the contacting rail section 8, and in turn to the contacting terminal 18 of the cutoff or closer 82. A 115 wire or lead 15^h is connected to the rail sections 12, and in turn to the stationary contact terminal 17^a of the cutoff 80. A lead or 120 wire 14^c connects to and forms a junction 14^a with the wire or lead 15^h. This wire or 125 lead 14^c is in turn connected to the contacting rail section 9. A wire or lead 14 connects the solenoid, and the contacting rail section 11. A wire 15 is connected to the rail section 6 and in turn to a junction 15^a. 130

with the wire 15^a which is in turn connected to the rail section 10. The wire or lead 15^a also forms a junction at 15^b with the wire 14. A wire or lead 13^a, which is connected to the 5 rail section 7 is in turn connected at 13^b with the wire 14. A wire 82^b is connected to a binding post of the motor 4 and in turn to the contact lug 82^a. Connected to the contacting lug 80^a is a wire 80^b which is connected at 80^c to the wire 82^b.

When a train is approaching the switch, the depressible device 67 in the cabin of the engine is depressed, causing the wheels 72 to engage the terminal rail sections 5 and 6, 15 thereby closing a circuit. In closing the 20 circuit the current passes from the battery or dynamo in the engine over the contacting rail section 5; the wire or lead 13 to the junction 15^c, and then to the stationary terminal 25 18 of the cutoff 82. The current then passes from the movable terminal 18^a over the contact lug 82^a over the wire 82^b to the motor 4, and from the motor to the solenoid 54 by way of the wire 62. The solenoid being 30 energized will draw the core 55 thereinto and lift the lever 56 then the eccentric rod 48 is free to be moved. The current passes from the solenoid over the wire 14 back to the battery or dynamo by way of the wires 35 15^a and 15, and the contacting rail section 6. The motor shaft 41 during the course of the current as just traced, is moving in the direction of the arrow *a*, and the lever 56 is raised in time whereby the eccentric 40 (which is operated by the shaft 41) may impart a reciprocating movement to the bar 49 and the eccentric rod 48, sufficient to operate the switch points 3^a and 4^a, so that the train can travel straight ahead. After completing 45 each half revolution of the motor shaft, the motor will automatically stop. For instance the contacting rail sections 5 and 6 are long enough, so that as long as the wheels 72 remain in contact with the rails 5 and 6, the motor will complete a half revolution. Supposing the switch points have been moved for a train moving straight ahead, and a following train is to take the siding. The depressible device 67 is then 50 depressed so that the wheels 72 will contact with the contacting rails 9 and 10, closing a circuit. The current of this circuit passes from the battery or the dynamo of the engine over the contacting rail 9, the wire or lead 14^c to the junction 14^a, and to the stationary contacting terminal 17^a of the cutoff 80. The current continues over the movable contacting member 17 shown in dotted lines in Fig. 1, over the lug 80^a, the wire or 55 lead 80^b, to the motor and thence to the solenoid, and back to the battery over the wires 14 and 15^a and the contacting rail 10. As before stated the solenoid is energized at such proper period to permit the motor to 60 operate and rotate the shaft 41 in the direc-

tion of the arrow *a*. The eccentric will then act to return the switch points to their full line positions as in Fig. 1, allowing the train to take the siding rails. As soon as the train reaches the siding rails, a depressible device 67 in the caboose or end car of the train may be actuated, so that wheels 72 may close a circuit on the contacting rails 7 and 8. The current of this circuit will pass over the wire 15^c, to the stationary contacting terminal 18 of the cutoff 82 over the terminal 18^a and the lug 82^a to the motor by way of the wire 82^b, and thence to the solenoid 54, and back to the battery in the caboose by way of the wires 14 and 13^a and the contacting rail section 7. The shaft 41 will move in the direction of the arrow *a* and the eccentric will operate and move the switch points, so that a next train can go straight ahead or may take the siding by closing the 75 circuit on the contacting rails 9 and 10. Upon a careful examination and upon following the directions of various trains, it is to be seen that other circuits may be closed for operating the switch points. For instance a train passing from a siding onto the main rail, a circuit may be closed on the contacting rail sections 11 and 12, so as to operate the switch points to their positions shown in Fig. 1 and after the train is passed 80 onto the main rails, the switch points may be restored by closing a circuit on the rail sections 5 and 6.

It is to be understood that the terminal rail sections 5 and 6, and 7 and 8, are to be 90 located far enough distant from the switch that the switch points may be easily thrown and securely locked. Also, the rail sections 5 and 6 may be short enough so that the train would need to slow to a speed of 95 100 safety for entering the siding, requiring time enough to pass over and allow time for the switch to throw and lock without the circuit being broken, by the contacting wheels passing off the ends of the contacting rail sections 5 and 6, where they are connected to the wiring 13 and 15. This would safeguard against accidents by engineers entering the sidings at dangerous speeds.

Also, there may be any conventional form 105 of signaling device in circuit with the switch throwing mechanism, to show whether the switch is set for the main line or the siding.

The invention having been set forth, what is claimed as new and useful, is:—

In a switch operating mechanism, the combination of the main rails and the siding rails, of switch points cooperating with the main rails, whereby a train may travel straight ahead or take the siding, an electric 115 motor having an intermittently driven shaft having an eccentric, means connecting the eccentric and the switch points, an electric circuit, means in said circuit for stopping the motor at every half revolution of its 120 125 130

shaft, and means carried by the train in circuit with a source of current supply on the train for closing the first circuit to operate the motor to rotate the shaft a half revolution, whereby the switch points may be opened or closed, said connections between the eccentric and the switch points having an eccentric rod provided with notches, and means actuated by the motor to be disconnected from one notch and dropped into en-

gagement with the other notch, for locking the switch points.

In testimony whereof I have signed my name to this specification in the presence of two subscribing witnesses,

CARLOS B. MICHENER.
